United States Patent Office

Des. 184,409
Patented Feb. 10, 1959

184,409

SEWING MACHINE OR SIMILAR ARTICLE

Martin R. Perla, Fairfield, Conn., and Malcolm S. Park, Verplanck Point, N. Y., assignors to The Singer Manufacturing Company, Elizabeth, N. J., a corporation of New Jersey

Application December 11, 1957, Serial No. 48,859

Term of patent 14 years

(Cl. D70—1)

Fig. 1 is a front perspective view of a sewing machine showing our new design,

Fig. 2 is a rear perspective view thereof.

The essential features of our design are shown in full lines in the drawings.

We claim:

The ornamental design for a sewing machine or similar article, as shown and described.
